UNITED STATES PATENT OFFICE.

JAMES T. GREELEY, OF NASHUA, NEW HAMPSHIRE, ASSIGNOR OF ONE-FOURTH TO
LUELLA L. GOOLD, OF PITTSBURGH, PENNSYLVANIA, AND ONE-FOURTH TO GUY H.
GEELEY, OF MERRIMAC, NEW HAMPSHIRE.

HYPODERMIC SYRINGE.

1,021,146.

Specification of Letters Patent. Patented Mar. 26, 1912.

Application filed July 14, 1911. Serial No. 638,551.

To all whom it may concern:

Be it known that I, JAMES T. GREELEY, a citizen of the United States, and a resident of Nashua, in the county of Hillsboro 5 and State of New Hampshire, have invented certain new and useful Improvements in Hypodermic Syringes, of which the following is a specification.

This invention relates to a hypodermic 10 syringe of the general character described in my application for Letters Patent of the United States filed March 25, 1911, Serial No. 616,934, said syringe comprising a collapsible capsule charged with liquid and 15 having a breast at one end and a contracted neck integral with the breast, said capsule, breast and neck being composed of ductile material, and a hypodermic needle inserted in the neck and having a practically non- 20 renewable connection therewith caused by the compression of the neck around the needle, the capsule being hermetically closed so that there is no outlet for the charge of liquid excepting through the lumen of the 25 needle.

The objects attained by the said syringe are asepsis and celerity, the needle permanently attached to the charged capsule being ready for immediate use and being in- 30 capable of a second use after the charge of liquid in the capsule has been ejected.

The present invention consists in the improvements hereinafter described and claimed in a hypodermic syringe character- 35 ized as above stated.

Of the accompanying drawings which form a part of this specification,—Figure 1 represents a longitudinal section of a hypodermic syringe embodying my invention, a 40 part of the capsule being shown in elevation; Fig. 2 represents a view similar to Fig. 1 showing the syringe inclosed in a holder and a stylet inserted in the lumen of the needle as a plug; Fig. 3 represents a 45 longitudinal section showing a portion of the holder and the stylet removed from the needle; Fig. 4 is a perspective view of the syringe, a portion of the capsule being broken off.

50 Similar reference characters indicate the same or similar parts in all the figures.

In the drawings,—12 represents a capsule, and 13 a hypodermic needle attached thereto. The capsule has no opening, except that

provided by the lumen of the needle, and 55 is charged with a liquid solution through one of its ends, the said end being closed and sealed after the insertion of the charge, so that the capsule is non-refillable.

The capsule is preferably a tube composed 60 of a ductile metal or alloy, such as that usually employed for collapsible tubes containing glue, paint, etc., the wall of the tube being relatively thin so that it may be collapsed and flattened by external pressure 65 between the thumb and fingers. One end of the tube is contracted to form a breast 14, the central portion of which is extended to form a tubular neck 15, integral with the breast and of much smaller diameter than 70 the main portion of the tube, the internal diameter of the neck being practically the same as the external diameter of the base portion of the needle. The base or inner end portion of the needle may be of any 75 suitable formation, whereby it is adapted to be interlocked with the material of the neck 15 to prevent endwise movement of the needle relatively to the neck.

In Figs. 1 and 2, I show the external 80 surface of the portion of the needle which enters the neck, roughened or corrugated, at 16. When the needle is inserted in the neck, the latter is compressed by a suitable tool to force portions of its material into 85 engagement with the prepared surface of the needle, thus establishing a suitable non-renewable union between the needle and the neck. If desired, the non-renewable union may be a solder joint, applied in any suit- 90 able way.

17 represents a stylet which is adapted to enter the lumen of the needle and constitute a plug to prevent leakage of liquid through the needle. The stylet is composed 95 of a single length of wire, formed to somewhat closely fit the lumen, the upper portion of the wire being formed into a series of coils, or otherwise bent to form an anchor 18.

The inner end of the neck 15 is provided with a cavity 19, the bottom of which surrounds the inner end of the needle 13. Before the capsule is charged, the stylet 17 is inserted in the lumen of the needle, the 105 inner end of the stylet projecting through the cavity 19. A filling 20 is then inserted in the cavity 19, said filling being of any

suitable material. The filling 20 and the protective body 23 hereinafter described may be of any suitable material, paraffin being preferred, this material being adapted 5 to liquefy at a temperature lower than the melting point of the material of the capsule, so that it may be sterilized by heat without injury to the capsule, and is adapted to solidify by cooling when in place. A 10 material such as collodion, adapted to solidify by evaporation, may be employed if desired. The said filling prevents contact of the liquid contents of the capsule with the needle, so that rusting and contamination 15 of the needle is prevented. The said filling is inserted in the cavity 19 before the capsule is charged and sealed. The filling 20 forms a liquid-tight packing around the stylet so that there is no possibility of leakage 20 of the liquid through or into the crevice surrounding the stylet. The filling 20 forms a hermetic seal around the inner end portion of the stylet which not only prevents leakage of liquid around the stylet 25 but also prevents access of dust, moisture and infection of any sort to the contents of the capsule.

21 represents a non-collapsible grip member of improved construction differing from 30 that shown in the above-mentioned application. The grip member 21 is a rigid ring preferably of metal, the opening of which is formed to closely embrace the periphery of the neck 15, the neck being crowded 35 tightly into the ring so that it is held firmly therein by frictional contact with the inner margin of the ring. The periphery of the ring is of about the same diameter as the capsule, so that it is adapted to support the 40 pressure of the thumb and finger of the hand in which the syringe is held, thus preventing such pressure from collapsing the capsule when pressure is exerted to force the needle into the skin. The construction of 45 the grip member heretofore employed was such that a solder connection between it and the neck was required. The annular grip member here shown requires no solder connection and furnishes a continuous supporting 50 surface entirely surrounding the neck 15.

22 represents a holder which is preferably a glass tube closed at one end and open at the opposite end, the tube being adapted to receive the capsule and needle as shown by 55 Fig. 2.

23 represents a body of protective material, which is preferably of the same material as the filling 20, and occupies the closed end of the holder and adheres thereto. The 60 point, and preferably the greater part of the projecting portion of the needle, together with the anchor 18 of the stylet 17, are embedded in the body 23 preferably while the latter is in a semi-fluid condition, 65 the needle containing the stylet being in-

serted in the holder before the material hardens. The protective body 23 not only prevents rusting or contamination of the external surfaces of the needle, but also prevents lateral movement of the needle in the 70 holder, the flattened end 12^a of the capsule extending across the holder and preventing lateral movement of the capsule therein. The open end of the holder 22 may be closed by a removable cap 24 of elastic rubber, 75 paraffin paper, etc.

When the needle is to be used, the cap 24 is removed and the capsule and needle are withdrawn from the holder, the body 23 of protective material retaining the stylet in the 80 holder, as indicated by Fig. 3. The withdrawal of the stylet from the filling 20 leaves an opening in said filling, said opening being a continuation of the lumen of the needle. The material of the filling 20 and 85 body 23 should be thoroughly sterilized so that no sterilization of the needle is required after its withdrawal from said body.

The form of the capsule is such that the flattening or collapsing of the entire capsule 90 will expel practically the entire charge of liquid through the needle, the collapsing pressure being applied by the thumb and fingers of the hand in which the capsule is held.

I claim:

1. A hypodermic syringe composed of a collapsible capsule charged with liquid and having a breast at one end and a neck integral with said breast, said capsule, breast 100 and neck being composed of ductile material, a hypodermic needle inserted in said neck and secured therein by the compression of the material of the neck around the needle, the neck being provided at its inner 105 end with a cavity, the bottom of which surrounds the inner end of the needle, a stylet inserted as a plug in the lumen of the needle, and a liquid-proof filling occupying said cavity and interposed between the needle 110 and the contents of the capsule, said filling constituting a hermetic seal around the stylet.

2. A hypodermic syringe composed of a collapsible capsule charged with liquid and 115 having a breast at one end and a neck integral with said breast, said capsule, breast and neck being composed of ductile material, a hypodermic needle inserted in said neck and secured thereto by the compression 120 of the material of the neck around the needle, and a rigid ring embracing and closely fitting said neck and constituting a continuous non-collapsible grip member.

3. In combination, a hypodermic syringe 125 composed of a collapsible capsule charged with liquid and having an integral neck at one end, a hypodermic needle inserted in said neck and having a permanent connection therewith, a stylet inserted in said 130

needle as a plug for the lumen thereof, said stylet having an anchor at its outer end, a holder inclosing the capsule and needle and having a closed end and an open end, and a body of protective material occupying the closed end of the holder and adhering thereto, the point of the needle and the anchor of the stylet being embedded in said body, whereby rusting of the needle point is prevented and the withdrawal of the capsule and needle from the holder causes the separation of the needle from the stylet, the latter remaining anchored in said body.

4. In combination, a hypodermic syringe composed of a collapsible capsule charged

with liquid, a hypodermic needle having a permanent connection with the capsule, a holder inclosing the capsule and needle and having a closed end and an open end, and a body of protective material occupying the closed end of the holder and adhering thereto, the point of the needle being embedded in said body.

In testimony whereof I have affixed my signature, in presence of two witnesses.

JAMES T. GREELEY.
